UNITED STATES PATENT OFFICE.

JOSEPH W. HUEBNER, OF MILWAUKEE, WISCONSIN.

MULTIPLE RESETTING-FUSE.

1,245,592.

Specification of Letters Patent.

Patented Nov. 6, 1917.

Application filed September 30, 1916. Serial No. 123,016.

To all whom it may concern:

Be it known that I, JOSEPH W. HUEBNER, a citizen of the United States, and resident of Milwaukee, in the county of Milwaukee, and State of Wisconsin, have invented certain new and useful Improvements in Multiple Resetting-Fuses; and I do hereby declare the following is a full, clear, and exact description thereof.

10 The present invention relates to new and useful improvements in fuses for electrical circuits and is more particularly directed to the provision of a device including a plurality of fuse elements adapted for selective inclusion in a circuit whereby should a fuse burn out, a fresh fuse may be immediately substituted.

It is the object of the present invention to provide a multiple fuse device which is 20 mechanically operable to position selective fuse elements in an electric circuit, more particularly with a view to providing a device which may be controlled from a distance.

The present device finds a particular application in connection with street car or other structures wherein a plurality of motors are provided, and to provide an indicating means for fuse members associated with respective motors, it is further an object to provide a signal adapted for actuation upon burning out of the fuse of a respective motor.

It is still further an object of the present invention to provide a multiple fuse structure wherein the fuse elements are so protected and housed that it is impossible to substitute copper strips or other freely conducting elements therefor, it being however also an object in this connection to provide a multiple fuse member which may be refilled upon breaking a certain seal and disassembling the structure.

With the above and other objects and advantages in view the invention resides more particularly in the novel combination, arrangement and formation of parts more particularly hereinafter described and particularly pointed out in the appended claims.

In the drawings.

50 Figure 1 is a vertical sectional view

through a multiple fuse constructed in accordance with the present invention.

Fig. 2 is a transverse sectional view taken through the structure immediately above the fuse drum as indicated by the line 2—2 of 55 Fig. 1.

Fig. 3 is a transverse sectional view through the intermediate portion of the drum on the line 3—3 of Fig. 1.

Referring now more particularly to the 60 accompanying drawings, there is provided a body drum 5, formed of porcelain or other suitable insulating material and provided with a series of spaced longitudinal channels 6 in its periphery adapted to receive 65 respective fuse strips 7. Inset in one end of the drum are a series of contact bars 8 which are mutually insulated and each connected with a fuse strip 7. Fitted over the other end of the drum, with its mouth portion extending into the channels is a cap 9 of suitable conducting material and having its mouth portion connected with the fuse strips to form a common contact member therefor. Disposed about the drum is a cylindrical casing 10 which has one end terminating adjacent the bars 8 and its other end extended about the cap 9 and terminating 75 flush with the respective end of the drum, thus completely closing the channels 6, and 80 this casing is secured on the drum by screws 11 passed therethrough, one of which screws has an apertured head adapted to receive a seal wire 12 passed through a lug 13 on the casing whereby unauthorized tampering 85 with the fuse structure, is prevented.

The fuses are preferably soldered to the bars 8 and the common contact cap 9, and extended through the channels in spaced relation to the walls thereof, and a packing 90 14 of asbestos or other suitable material is disposed in the channels about these fuse strips.

The fuse drum is rotatably mounted on a suitable support by means of upper and 95 lower shafts 15 and 16 respectively, the upper shaft being permanently carried in a bracket 17 and having a squared end loosely fitting into a corresponding socket 18 in that end of the drum carrying the contact bars 100.

8. The other shaft is detachably held in a sleeve bracket 19 by a set screw 20 and is adapted to fit in a socket portion 21 of the bottom of the common contact cap 9, the adjacent end of the drum being correspondingly socketed to receive this portion. The socket portion 21 and the end of the shaft 16 are preferably tapered to provide a proper conducting contact.
10. Connected with the bracket 19 is one end of a conducting cable 22 and thus current is adapted to pass through the bracket, the shaft, the common contact cap 9 and through one of the fuse strips to a respective contact bar 8. To take current selectively from one of the contact bars, a brush 23 is carried by a suitable bracket 24, this brush and the bars 8 corresponding in general construction to the armature and brush of a motor. Thus should a respective fuse strip "burn out," the drum may be rotated one step to thus place a second fuse strip in the circuit.
- To provide for this step by step rotation of the drum, the shaft 15 carries a ratchet wheel 26 at one end, having teeth on its upper side, and mounted above this ratchet wheel is a solenoid 27 having an armature 28 resiliently urged downwardly by a spring 29 and connected with one end of an angular lever 30, which is pivoted at its angle and carries at its other end a pawl 31 engageable with the teeth of the ratchet wheel. This solenoid is included in an electric circuit 32 including the batteries 33, ground connections 34 and a suitable resistance 35, the switch being preferably disposed for convenient operation at a distance from the fuse structure whereby a maximum convenience is afforded in providing a fresh fuse element in the main circuit.
- Particularly in connection with street cars or other structures wherein a plurality of motors are employed, it is desirable to provide a signal means for indicating the blowing of a respective fuse, and to accomplish this, there is provided a circuit 37 connected with the bracket 19 and the brush structure, and including a lamp 38 preferably mounted adjacent the switch 35. Thus when the fuse is intact, the current will flow therethrough and the lamp will be short circuited, but upon burning of the fuse the lamp will be lighted.
- The fuse drum 5 is removed and replaced by withdrawing the shaft 16 from its bracket 19, and may be disassembled by breaking the seal 12 and withdrawing the casing 10, to provide for refilling the fuse, it being noted, however, that an unauthorized tampering with the fuse element is prevented due to the seal 12.
- I claim:
1. A multiple fuse comprising a rotatably mounted drum, a common contact member
- at one end thereof, contact bars at the other end of the drum, fuse strips connecting said common contact member and the contact bars, a brush for selectively engaging said contact bars, a casing disposed about the drum, a detachable connection between the casing and drum, and a seal associated with said connection.
2. A multiple fuse comprising a cylindrical body provided with a series of longitudinal channels in its periphery and terminating short of the ends of the channel, fuse strips disposed in said channels, a common contact member connected with the fuse strips at one end of the body, contact bars connected with the fuse strips at the other end of the body and a casing detachably secured to the body for closing the channels.
3. A multiple fuse comprising a drum, longitudinal fuse strips carried by the drum, a common contact member at one end of the drum connecting the fuse strips and provided with a socket arranged axially of the drum, contact bars at the other end of the drum, a brush selectively engageable with said bars, a shaft having detachable interlocking engagement with the last named end of the drum, a detachable shaft engageable in the socket of the common contact member and means for rotating the first named shaft in successive steps.
4. A multiple fuse comprising a rotatably mounted drum, a series of spaced longitudinal channels in the periphery thereof, a common contact member at one end of the drum, contact bars at the other end of the drum, fuse strips disposed in said longitudinal channels and connecting said common contact member and the contact bars, non-conducting packing in the longitudinal channels and surrounding the fuse strips, and a brush for selectively engaging said contact bars.
5. A multiple fuse comprising a drum, a common contact member in the form of a cap at one end thereof, contact bars at the other end of the drum, fuse strips connecting said common contact member and contact bars, pivot members rotatably supporting the drum, a brush for engaging one of said contact bars, and means carried by one of said pivot members for rotating the drum step by step to cause said brush to selectively engage said contact bars.
6. A multiple fuse comprising a drum, longitudinal fuse strips carried by the drum, a common contact member at one end of the drum connecting the fuse strips, contact bars at the other end of the drum, a brush selectively engageable with said bars, a shaft having interlocking engagement with the last named end of the drum, a shaft engageable centrally with said common contact member, and means for rotating the

drum in successive steps, said means consisting of a ratchet wheel formed on the upper end of the shaft engaging the upper end of the drum, a pawl adapted to engage 5 the teeth of the ratchet wheel, and means for causing the pawl to rotate the ratchet wheel, substantially as described.

In testimony that I claim the foregoing

I have hereunto set my hand at Milwaukee, in the county of Milwaukee and State of Wisconsin, in the presence of two witnesses.

JOSEPH W. HUEBNER.
